UNITED STATES PATENT OFFICE

93,712

DESIGN FOR A CHAIR FRAME

Philip E. G. Ericson, St. Charles, Ill., assignor to
The W. H. Howell Company, Geneva, Ill., a cor-
poration of Illinois

Application February 12, 1934, Serial No. 50,695

Term of patent 7 years

To all whom it may concern:

Be it known that I, PHILIP E. G. ERICSON, a citizen of the United States, residing at St. Charles, in the county of Kane and State of Illinois, have invented a new, original, and ornamental Design for a Chair Frame, of which the following is a specification, reference being had to the accompanying drawing, forming a part thereof, wherein—

Figure 1 is a perspective view of a chair frame, looking from the front and side showing the upwardly and rearwardly arched design of the arm

portions of the side supporting frame members, also the centrally arched portions of the floor engaging portions of said frame members which constitute dominant features of the instant design for chair frames; and

Fig. 2 is a side elevation of a chair frame, showing my new design.

I claim:

The ornamental design for a chair frame, as shown and described.

PHILIP E. G. ERICSON.
